UNITED STATES PATENT OFFICE.

GEORGE W. HAWLEY, OF BRIDGEPORT, CONNECTICUT, ASSIGNEE TO KNY-SCHEERER CORPORATION, OF NEW YORK, N. Y., A CORPORATION OF NEW YORK.

FOOT-SUPPORT.

1,239,789.

Specification of Letters Patent. Patented Sept. 11, 1917.

Application filed June 30, 1916. Serial No. 106,377.

To all whom it may concern:

Be it known that I, GEORGE W. HAWLEY, a citizen of the United States, residing at Bridgeport, in the county of Fairfield and State of Connecticut, have invented certain new and useful Improvements in Foot-Supports, of which the following is a specification.

This invention relates to a foot support to be used in connection with fracture and orthopedic tables, and its novelty consists in the construction and adaptation of the parts as will be more fully hereinafter described.

It often becomes necessary while operating upon a patient on a fracture and orthopedic table to move the leg and foot of the patient without changing the relative position of any of the bones of the leg and foot but it has been impossible to do this with mechanical certainty heretofore.

My invention meets that demand and enables the operator to change the position of the leg and foot of the patient with such mechanical nicety that the relative positions of the bones of the foot and leg are not affected in the slightest degree.

Also, any desired flexion can be accomplished and any desired traction exerted and the limb immobilized in plaster in the position desired.

In the drawings, Figure 1 is a miniature perspective of a fracture and orthopedic table showing its use by means of the patient in dotted outline thereon; Fig. 2 is an enlarged perspective of the foot support in use showing certain operative parts in section; Fig. 3 is an end view of the foot support showing one of the possible changes of position, in dotted outline.

In the drawings 4 is a fracture and orthopedic table having two traction bars 5 on each of which is slidably mounted by means of wing nuts 7 and bolts 9, a sub-frame 6. This sub-frame 6 carries a T telescope rod 8 which is held in the tube 18 of the sub-frame by a set screw 25. A threaded bar 10 is loosely mounted in the head of the rod 8 at 11, and a nut 12 having a handle 13 is threaded to engage the bar 10 at one end. A winged lock nut 14 threaded to engage the bar 10 holds a foot-piece 15 with a washer 16 between in a fixed position on the opposite end against a head 17 of the bar 10, and bears against a shoulder 23 of the telescope rod 8. The foot-piece 15 has a downwardly turned

plate member 19 which has an upturned edge 27. Binding posts 24 are made integral with rod 8.

This device is adapted to be used in connection with an orthopedic table Patent No. 1,126,460, as well as with others, and reference to that is made for a complete description of the use of the table.

In use the foot of the patient (20 in Fig. 2) to be treated is secured in a fixed position by placing the ball of the foot against the plate 19 with the outside of the foot against the upturned edge 23, an anklet 21 being secured to the foot and straps 22 secured to the anklet 21 at one end and to binding posts 24 at the other end.

The telescope rod 8 can be raised or lowered manually to the desired height and secured in position by the set screw 25 engaging either of the internally threaded 75 housings 26. By turning the handle 13 of the nut 12 to the left, the threaded bar 10 will be pushed toward the foot of the patient and contrariwise by the turning to the right. In this way the desired traction on 80 the bone to be treated is obtained. The foot-piece 15 can be turned to the desired angle by first turning the nut 12 to the left so as to move the threaded bar 10 toward the foot 20 until wing nut 14 is clear of shoulder 25, and 85 then turning the wing nut 14 to the left. Wing nuts 9 can then be loosened and the foot support 15 and the leg can be moved to one side or the other at the same time without changing the relative upright position of 90 the foot to the leg, as shown in dotted outline in Fig. 3.

The device here shown and described is merely a preferred form, and changes in the construction, arrangement and disposition of 95 the several parts may be made without in any way departing from the field and scope of my invention.

I claim:

1. A foot support comprising a sub-frame 100 and a foot piece carried by the sub-frame, said sub-frame being wholly supported on an orthopedic or fracture table, and being longitudinally adjustable with respect to the table, said foot piece being adjustable vertically, transversely and axially relative to the sub-frame. 105

2. A foot support comprising a sub-frame and a foot piece carried by the sub-frame, said sub-frame being wholly supported on 110

- an orthopedic or fracture table, and being longitudinally adjustable with respect to the table, said foot piece being vertically adjustable and axially pivoted on the sub-frame. 55
3. A foot support comprising a sub-frame and a foot piece, said foot piece being adjustably carried by the sub-frame, said sub-frame being wholly supported on an orthopedic or fracture table, and being longitudinally adjustable with respect to the table, the foot piece having perpendicular and axial adjustment with respect to the sub-frame and the sub-frame being revolvable on the table. 60
4. A foot support adapted to be used in connection with an orthopedic and fracture table the sub-frame of which is mounted for longitudinal movement on said table, a **T** telescope rod slidably adjustable in a tube of said sub-frame, in combination with a foot-piece revolvable in its own plane and adapted to be moved longitudinally with respect to said table. 65
5. A foot support comprising a sub-frame adapted to be adjustably clamped to an orthopedic and fracture table, a telescoping member adjustably mounted therein, a threaded bar adapted to be moved longitudinally to the table mounted in the head of the telescoping member and a foot-piece adjustably mounted on said threaded bar so that it can be secured at any angle desired in its own plane. 70
6. A foot support mounted by adjustable clamps having a **T** telescope rod slidably adjustable in a tube of a sub-frame, a foot-piece revolvable in its own plane and adapted to be moved longitudinally of a patient's leg, in combination with a fracture and orthopedic table having pivoted traction bars on which said sub-frame is adjustably mounted. 75
7. A foot support comprising a sub-frame adapted to be adjustably mounted by clamps, a telescoping member mounted therein so as to be vertically adjustable, a threaded bar adapted to be moved longitudinally of a patient's leg mounted in the head of the telescoping member, and a foot-piece adjustably mounted on said threaded bar so that it can be secured at any angle desired in its own plane, in combination with a fracture and orthopedic table having pivoted traction bars on which said sub-frame is adjustably mounted. 80
8. A foot support adapted to be used in connection with an orthopedic and fracture table the sub-frame of which is mounted thereto by adjustable clamps, a **T** telescope rod slidably adjustable in a tube of said sub-frame, in combination with a foot-piece having an upturned edge revolvable in its own plane and adapted to be moved longitudinally with respect to said table. 85
9. A foot support comprising a sub-frame adapted to be adjustably clamped to an orthopedic and fracture table, a telescoping member adjustably mounted therein, a threaded bar adapted to be moved longitudinally to the table mounted in the head of the telescoping member and a foot-piece having an upturned edge adjustably mounted on said threaded bar so that it can be secured at any angle desired in its own plane. 90
10. A foot support having a foot piece with an upturned edge mounted by adjustable clamps having a **T** telescope rod slidably adjustable in a tube of a sub-frame, a foot-piece revolvable in its own plane and adapted to be moved longitudinally of a patient's leg, in combination with a fracture and orthopedic table having pivoted traction bars on which said sub-frame is adjustably mounted. 95
11. A foot support having a foot piece with an upturned edge comprising a sub-frame adapted to be adjustably mounted by clamps, a telescoping member mounted therein so as to be vertically adjustable, a threaded bar adapted to be moved longitudinally of a patient's leg mounted in the head of the telescoping member, and a foot-piece adjustably mounted on said threaded bar so that it can be secured at any angle desired in its own plane, in combination with a fracture and orthopedic table having pivoted traction bars on which said sub-frame is adjustably mounted. 90

In testimony whereof I affix my signature in presence of two witnesses.

GEORGE W. HAWLEY.
